[57] CLAIM

The ornamental design for a combined shoreline protective structure and water purification structure, as shown and described.

DESCRIPTION

FIG. 1 is a perspective view of a combined shoreline protective structure and water purification structure showing my new design. The broken line showing is for illustrative purposes only;

FIG. 2 is a fragmentary elevation of a portion of the structure as seen from the shoreline; and,

FIG. 3 is a fragmentary elevation of a portion of the structure as seen from the ocean side looking toward the shore.
